UNITED STATES PATENT OFFICE.

FRANK R. BUCK, OF SAN FRANCISCO, CALIFORNIA.

COMBINED BED OR COUCH AND BATH.

SPECIFICATION forming part of Letters Patent No. 761,443, dated May 31, 1904.

Application filed March 5, 1904. Serial No. 196,686. (No model.)

To all whom it may concern:

Be it known that I, FRANK R. BUCK, a citizen of the United States, residing at San Francisco, in the county of San Francisco and State 5 of California, have invented certain new and useful Improvements in a Combined Bed or Couch and Bath, of which the following is a specification.

My invention relates to a combined couch 10 and vapor or hot-air bath, the object of my invention being to provide an apparatus which when closed shall make a strong, durable, and convenient couch or bed or a useful article of furniture suitable for a sleeping-room, sitting- 15 room, or office convenient for professional or private use and which when open can be used for a steam-bath or a hot-air bath, and particularly to provide an apparatus of this character which when used as a vapor or hot-air bath 20 shall be free from the objectionable features of producing a suffocating feeling or a weakening effect upon the bather experienced in many other devices of this character now in use, but, on the other hand, shall act as a tonic, producing 25 a vigorous reaction, stimulating poor circulation, and cleansing the pores of the skin without undue fatigue.

My invention is also intended to be used with suitable changes as a spray, sponge, hip 30 bath, or for a sun or colored-light bath.

In the accompanying drawings, Figure 1 is a perspective view of the apparatus used as a couch or bed. Fig. 2 is a similar broken view 35 showing the apparatus partly open for the purpose of using it as a bath. Fig. 3 is a horizontal section of the hot-air chamber. Fig. 4 is a perspective view of the apparatus fully opened and in use as a bath. Fig. 5 is a horizontal section of the bath-chamber, 40 partly folded up. Fig. 6 is a vertical cross-section of the hot-air chamber on the line B B of Fig. 3.

Referring to the drawings, 1 represents a suitable main frame supported upon casters 2 45 and having a bottom 3 and sides 4. On one side thereof is hinged a lid 5, having at the ends cleats 6, which fit down over the ends of the frame and supported when opened by means of oblique stays 7, which are remov-

ably attached in the usual manner for supporting swinging lids. Upon said lid is a spring-mattress 8 and a cover 9 for use as a couch or bed.

The main frame is divided by a vertical wall 10 into two portions—a smaller portion 11, 55 which may be called a "vestibule," and a larger portion 12, which contains the bathing-chamber. The side 4 of the main frame at the entrance to the vestibule is cut down and provided with a hinged shutter 13, which is 60 raised and attached by means of a hook and eye in the usual manner when the apparatus is used as a couch, and when the apparatus is used for bathing said shutter is let down, leaving a low wall or entrance to the vestibule. 65 At the end of the main frame next the vestibule there is provided a transverse shelf or seat 14, upon which the bather can sit when preparing to enter the bath or after having bathed and when partially or wholly drying 70 himself before stepping out of the vestibule. It is also useful for chiropodistic operations after bathing. It is furthermore of great utility in providing a suitable place for an attendant when one is needed and for the purpose of applying the electric treatment while 75 in the bath. On the under side of the lid and at the end of the vestibule opposite to the entrance when the lid is raised is secured a receptacle 15 for a mirror 16, a timepiece 17, 80 racks 18 for towels, and a rack 19 for brushes or other toilet articles.

20 is a shelf or seat extending transversely of the main frame and forming the top of the hot-air chamber 21. The transverse wall 10 85 next to the vestibule-entrance is cut away, as shown at 22, to permit the insertion of the stove 23 for generating heat for the bath. The top 20 is formed with an opening 24 over said stove, and a boiler 25 is supported there-over, from which the steam issues by a pipe 26, leading down through a hole 45 into an extension 27 from the bathing-chamber under the seat 20. The products of combustion from the stove are led from said hot-air chamber 21 90 by means of a short elbow 28, having a swinging connection with a pipe 29, loosely supported upon the under side of the lid, and

forming a draft-pipe for carrying the products of combustion upward when the device is opened.

The walls and top of the bathing-chamber 5 are all supported on the under side of the lid, for which purpose said lid has secured thereto narrow strips 30 transverse to the lid and a strip 31, joining said transverse strips and extending longitudinally of the lid. To the strip 10 30 on the far side from the vestibule is hinged the rear wall 32 of the bathing-chamber, to which again is secured a narrow strip 33, having hinged thereto the side wall 34 of the bathing-chamber, to the other vertical edge 15 of which is again hinged a portion 35 of the front wall of said chamber.

47 is a cleat secured to the lower edge of the wall 34, the better to support the same. To the front transverse strip 30, next the vestibule, is hinged a portion 36 of the front wall, to which again is hinged a second portion 37. Upon the upper edge of the rear wall 32 is hinged the top of the bathing-chamber, which is in four parts—a rear part 38, hinged directly to said rear wall, a part 39, hinged to the free edge of the part 38 and extending over the bathing-chamber next to the lid, a part 40, hinged to the part 39 and extending in front of the bather's head, and a part 41, 25 hinged to the part 38 and lying down upon the far side of the bathing-chamber from the lid. The frame has secured thereon at the rear of the bathing-chamber a shelf or seat 42, and also at the side of the bathing-chamber opposite to the lid is hinged a shelf or seat 43, supported when in use by turn-buttons 44, which extend over the shelves or seats 42 and 20. By reason of this construction the bather can turn around when in the vapor-chamber, when in any such position the feet extending beneath one of these shelves or seats, so that ample room is provided to sit in a comfortable position without unduly enlarging said chamber.

45 46 represents a thermometer in the bathing-chamber.

48 is a drain-pipe for drawing off the water from the bath.

It will readily be understood that instead 50 of an oil-stove, as is here shown, an alcohol-stove may be used or a gas-stove suitably connected by a flexible pipe with a gas-burner.

I claim—

1. A combined couch or bed and bath comprising a box-like frame, a removable lid therefor, having a yielding or resilient upper surface to form a bed or couch, sides of a bath-cabinet folded within said frame, and means for supporting said sides upon said frame to form a bath-cabinet, substantially as described.

2. A combined couch or bed and bath comprising a box-like frame, a lid hinged to said frame, and having a mattress on the upper

side thereof, sides of a bath-cabinet folded 65 within said frame, and means for supporting said sides, when open, upon said frame and lid, substantially as described.

3. A combined couch or bed and bath comprising a box-like frame, a lid hinged thereon, 70 and provided with a yielding upper surface to form a bed or couch, sides of a bath-cabinet movably supported upon the under side of the lid, and means for supporting said sides, when open, to form a bath-cabinet, substantially as 75 described.

4. A combined couch or bed and bath comprising a box-like frame, a hinged lid therefor, a partition dividing said frame into two compartments, a seat on the frame adjacent to 80 one of said compartments, and means for supporting a bath-cabinet over the other compartment, substantially as described.

5. A combined couch or bed and bath comprising a box-like frame, a partition dividing 85 the frame into a vestibule-compartment and a bathing-compartment, means for supporting the sides of a bath-cabinet over the latter compartment, a stove between the two compartments, and a second partition forming with 90 the first partition a hot-air chamber between two compartments, substantially as described.

6. A combined couch or bed and bath comprising a box-like frame, a hinged lid therefor, partitions in said frame forming a hot-air 95 chamber, and located medially of the frame to divide the same into two compartments, means for supporting knockdown sides of a bath-cabinet over one of said compartments, the side of the frame being cut down at the entrance to the other compartment, and a shutter filling the cut-down portion when the apparatus is closed for use as a bed, substantially as described.

7. A combined couch or bed and bath comprising a box-like frame, a lid hinged thereto, 105 seats at the top of said frame, knockdown sides of a bath-cabinet supported partly by said lid, and arranged over said frame within said seats whereby the space beneath the seats 110 forms a lower extension of the bath-chamber, substantially as described.

8. A combined couch or bed and bath comprising a box-like frame, a lid hinged thereto, 115 seats at the top of said frame, one of said seats being hinged to fall down to allow the lid to close, knockdown sides of a bath-cabinet supported partly by said lid, and arranged over said frame within said seats whereby the space beneath the seat forms a lower extension of 120 the bath-chamber, substantially as described.

9. A combined couch or bed and bath comprising a box-like frame, a hinged lid therefor, a partition dividing the frame into compartments, a knockdown bath-cabinet and 125 means for supporting the same over one of said compartments, and means for holding toilet articles, secured to the under side of the

lid and received within the other compartment when the lid is closed, substantially as described.

10. A combined couch or bed and bath comprising a box-like frame, a hinged lid therefore, partitions extending transversely of the frame medially thereof and dividing the frame into two compartments, a seat or top covering the space between said partition and forming a hot-air chamber and opening at the end of one of said partitions to permit the insertion of a stove into the end of said hot-air chamber, an opening at the end of said top over which to place a boiler, means for supporting a knockdown bath-cabinet over one of said compartments, and means for admitting steam from the boiler into said cabinet, substantially as described.
11. A combined couch or bed and bath comprising a box-like frame, a hinged lid therefore, partitions extending transversely of the frame medially thereof and dividing the frame into two compartments, a seat or top covering the space between said partition and forming a hot-air chamber and opening at the end of one of said partitions to permit the insertion of a stove into the end of said hot-air chamber, an opening at the end of said top over which to place a boiler, a flue movably connected with the hot-air chamber and supported upon the under side of the lid, means for supporting a knockdown bath-cabinet over one of said compartments, and means for admitting steam from the boiler into said cabinet, substantially as described.

12. A combined couch or bed and bath comprising a box-like frame, a hinged lid therefore, transverse seats at the top of said frame, a longitudinal seat between said transverse seats, hinged to the side of the frame, means for supporting said longitudinal seat upon the transverse seats, and knockdown walls of a bath-cabinet movably supported upon the lid

and received between the transverse shelves when the lid is closed, substantially as described.

13. A combined couch or bed and bath comprising a box-like frame, a hinged lid therefore, a transverse partition dividing the frame into two compartments, knockdown walls of a bath-cabinet supported by said lid over one of said compartments, walls of a receptacle supported on the under side of said lid opposite to the other compartment, racks contained between said walls, and a swinging mirror contained in the receptacle, substantially as described.

14. A combined couch or bed and bath comprising a box-like frame, a hinged lid therefore, strips secured upon the under side of said lid, walls of a bath-cabinet hinged to said strips, and a top of said chamber hinged to one of said walls, substantially as described.

15. A combined couch or bed and bath comprising a box-like frame, a lid hinged to said frame, walls of a bath-cabinet movably supported by said frame, a wall of said cabinet movably attached to one of the aforesaid walls, and a top of said cabinet movably attached to one of said walls, substantially as described.

16. A combined couch or bed and bath comprising a box-like frame, a lid hinged to said frame, walls of a bath-cabinet movably supported by said frame, a wall of said cabinet movably attached to one of the aforesaid walls, and a top of said cabinet movably attached to one of said walls, said top being in sections hinged together, substantially as described.

In witness whereof I have hereunto set my hand in the presence of two subscribing witnesses.

FRANK R. BUCK.
